UNITED STATES PATENT OFFICE.

ROSWELL A. MOORE, OF WATERBURY, CONNECTICUT, ASSIGNOR TO WATERBURY
BUCKLE COMPANY, A CORPORATION OF CONNECTICUT.

DESIGN FOR AN ARMBAND.

44,716.

Specification for Design.

Patented Oct. 7, 1913.

Application filed April 23, 1913. Serial No. 763,171. Term of patent 7 years.

To all whom it may concern:

Be it known that I, ROSWELL A. MOORE, a citizen of the United States, residing at Waterbury, New Haven county, Connecticut, have invented a new, original, and ornamental Design for Armbands, of which the following is a specification, reference being had to the accompanying drawing, forming part thereof.

The figure is a perspective view of an arm band showing my new design.

I claim:

The ornamental design for an arm band, as shown.

ROSWELL A. MOORE,

Witnesses:

H. C. COOLEY,
W. T. BRONSON.
